UNITED STATES PATENT OFFICE.

PETER R. DILL, OF CLEVELAND, AND JOHN W. SWARTZ, OF LAKEWOOD, OHIO, ASSIGNEES TO THE BANKERS SAVINGS & CREDIT SYSTEM COMPANY, OF CLEVELAND, OHIO, A CORPORATION OF OHIO.

COIN BANK.

Application filed September 29, 1922. Serial No. 591,224.

To all whom it may concern:

Be it known that we, (1) PETER R. DILL, (2) JOHN W. SWARTZ, citizens of the United States, residing at (1) Cleveland, (2) Lakewood, in the county of Cuyahoga and State of Ohio, have invented certain new and useful Improvements in Coin Banks, of which the following is a full, clear, and exact description, reference being had to the accompanying drawings.

Our invention relates to pocket coin banks or receptacles and it has for its object to provide a comparatively simple and cheap device of the aforesaid character which is compact and is particularly convenient of use, the same being of such nature as to facilitate the insertion of coins through the receiving opening, the removal of coins through the discharge opening, and to insure against coins being extracted from the bank through the receiving opening.

These objects, with others pertaining in most part to structural refinements, are attained in the construction illustrated in the drawing which accompanies and forms a part hereof and wherein Fig. 1 is a perspective view of our improved coin bank or receptacle. Figs. 2 and 3 are elevational views of the bank showing it in coin receiving and coin transferring positions, respectively; Figs. 4, 5 and 6 are sectional views, the plane of section being indicated by the line 4—4 of Fig. 2, showing the bank in coin receiving, coin transferring, and coin discharging positions, respectively; Fig. 7 is an inside elevational view of the cover; Figs. 8 and 9 are sections on the respective lines 8—8 and 9—9 of Fig. 4; and Fig. 10 is a view of the key by means of which the bank is unlocked.

The bank comprises two circular casing members which, for convenience of description, may be referred to as the receptacle A and the cover B. The receptacle A, has a circular wall a and a shallow cylindrical wall a' beyond which the edge of the circular wall a extends to provide a flange a^2 which is preferably knurled. The cover B has a circular wall b and a cylindrical wall b' which telescopes over the corresponding wall a' of the receptacle; and the edge portion of the circular wall b protrudes beyond the cylindrical wall b' to form a flange b^2 , also preferably knurled. A post a^3 is dis-

posed centrally within the receptacle and connects the circular walls of the receptacle and cover, as by having its ends reduced and extended through apertures in the walls and upset or riveted therebeyond (see Fig. 8).

The wall a' of the receptacle is notched at a^5 to a depth somewhat greater than the thickness of a coin for which the bank is designed, and a shoulder a^6 is formed on the post a^3 in the plane of the bottom of the notch a^5 , preferably by reducing the end of the post adjacent the cover.

A coin pocket a^7 , suitably constructed of resilient sheet metal, has its inner end provided with an aperture that is engaged over the reduced end of the post a^3 so that it will rest upon the shoulder a^6 , while its outer end is designed to fit within the notch a^5 of the wall a' . This holds the pocket against turning with respect to the receptacle. A tongue a^8 is turned laterally from the end of the pocket and engages the inner side of the wall a' for a purpose which we shall presently explain. A flange a^{10} extends along one side of the pocket from its inner to its outer end and the same is of a depth sufficient to close that side of the pocket by cooperation with the wall b . Extending from the opposite side of the pocket are tongues a'' that are inclined upwardly toward their outer ends for frictional contact with the wall b of the cover. The part a^{12} of the inner end of the pocket is elevated slightly above the plane of the body portion of said pocket for a purpose presently to be explained. The cylindrical wall a' of the receptacle is cut away to provide an opening a^{13} which is shown as diametrically opposite the notch a^5 ; and the wall b' of the cover is cut away to provide an opening b^3 of substantially the same width as the aforesaid opening a^{13} . A push pin b^4 is carried by the circular wall b of the cover, and when the parts are in coin receiving position, as illustrated in Figs. 1, 2 and 4, the push pin b^4 reposes along side the flange a^{10} of the pocket a^7 . The pin b^4 is in the arcuate path of the space between the tongues a'' . A spring latch b^5 is secured as by rivets b^6 , to the circular wall b of the cover, and its nose b^7 engages the inner surface of the cylindrical wall a' when the parts are in coin receiving position.

With the parts in such position, a coin may be inserted through the opening b^3 and notch a^5 into the coin pocket a^7 , and when the cover is then turned with respect to the receptacle in the direction indicated by the arrow in Fig. 1, the push pin b^4 will shove the coin out of the pocket past the tongues a'' into the coin receptacle, the edge of the coin, in the meantime, riding beneath the elevated portion a^{12} of the inner end of the pocket, insuring the coin being freed from the fingers a'' . The movement of the cover in the aforesaid direction is limited by the engagement of the nose of the latch b^5 with the end of the wall a' on one side of the discharge opening a^{13} . This position of the parts illustrated in Fig. 5 has hereinbefore been referred to as coin transferring position. In order to move the parts to the coin discharging position, or that shown in Fig. 6, a key C is inserted through the key-hole b^8 in the cover, between the body portion of the latch b^5 and a rigid abutment portion b^9 thereof, turned in an appropriate direction to swing the latch b^5 inwardly and free its nose b^7 from the end of the wall a' , after which the cover may be rotated to bring its opening b^3 into register with the discharge opening a^{13} of the receptacle.

In order to prevent the removal of coins from the bank, should the outer end of the coin pocket a^7 be bent upwardly or deformed, the previously mentioned tongue a^9 is turned downwardly from the end of the pocket inside the wall a' to obstruct the notch a^5 .

Having thus described our invention, what we claim is:

1. A coin bank comprising relatively rotatable casing members enclosing a coin compartment having a coin receiving opening, a coin pocket in receiving relation to said opening, and means for transferring a coin from the pocket to the compartment when the casing members are relatively rotated.

2. A coin bank comprising relatively rotatable casing members enclosing a coin compartment and having a coin receiving opening, a coin pocket in receiving relation to said opening, means for transferring a coin from the pocket to the compartment when the casing members are relatively rotated, and means preventing the passage of coins from the compartment to the pocket.

3. A coin bank comprising a casing enclosing a coin compartment having a coin receiving opening, said casing incorporating relatively movable parts, a coin pocket in receiving relation to said opening, and means for transferring a coin from the pocket to the compartment when the aforesaid parts are moved with respect to each other.

4. A coin bank comprising relatively rotatable casing members enclosing a coin compartment and having a coin receiving opening, a coin pocket in receiving relation to said opening, means for transferring a coin from the pocket to the compartment when the casing members are relatively rotated, means preventing the passage of coins from the compartment to the pocket, the last mentioned means frictionally engaging the coins during their discharge from the pocket, and a part engaging the coin for freeing it from said last mentioned means at the completion of the transferring operation.

5. A coin bank comprising relatively movable casing members each having a wall which overlies a wall of the other, the casing enclosing a coin compartment and having a coin receiving opening, means preventing the discharge of coins from the receiving opening, the aforesaid walls of the respective casing members having openings which when brought into register with each other provide a discharge opening for the coin compartment, means for preventing relative movement of the casing members to a position wherein said openings register, and further means for rendering the former ineffective.

6. A coin bank comprising relatively rotatable casing members having peripheral walls telescoping one with the other, the inside peripheral wall having a coin receiving slot and a coin discharge slot that are spaced apart circumferentially of said wall, the outer peripheral wall having an opening which is adapted to be brought into register with either the coin slot or the coin discharge opening, a spring latch carried by the casing member having the outer peripheral wall and bearing against the inner side of the inner peripheral wall and being so disposed with respect thereto that when the casing member whereby the latch is carried is rotated in a given direction said latch will engage the end of the inner peripheral wall which constitutes one end of the coin discharge opening of said wall, and means for releasing the latch whereby the casing members may be rotated to a position wherein the opening of the outer peripheral wall is in register with the discharge opening of the inner peripheral wall.

7. A coin bank comprising two circular casing members having cylindrical peripheral walls which telescope one within the other, a stud disposed centrally within the casing and connecting the casing members together while permitting them to rotate one with respect to the other, the inner peripheral wall having a coin slot and a coin discharge opening, and the outer peripheral wall having an opening adapted to be brought into register with either the slot

or the discharge opening, means preventing the discharge of coins through the coin receiving slot, means for preventing relative rotation of the casing members to a position wherein the opening of the outer peripheral wall registers with the discharge opening of the inner peripheral wall, and

further means for rendering the last mentioned means ineffective.

In testimony whereof, we hereunto affix 10 our signatures.

PETER R. DILL.
JOHN W. SWARTZ.
